[57] **CLAIM**

The ornamental design for an information input/output managing machine equipped with a text creating function, as shown and described.

DESCRIPTION

FIG. 1 is a front, bottom and right side perspective view of an information input/output managing machine equipped with a text creating function, showing my new design;
FIG. 2 is a front elevational view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a rear elevational view thereof;
FIG. 8 is a front, bottom and right side perspective view thereof with a cover half-closed and a pen removed; and,
FIG. 9 is a front, bottom and right side perspective view thereof with a cover in a closed state.
